UNITED STATES PATENT OFFICE.

LIZZIE O. KOONES, OF BROOKLYN, NEW YORK.

DESIGN FOR CARD-BASKETS OR ORNAMENTS.

SPECIFICATION forming part of Design No. 11,568, dated January 6, 1880.

Application filed December 12, 1879. Term of patent 3½ years.

To all whom it may concern:

Be it known that I, LIZZIE O. KOONES, of Brooklyn, in the county of Kings and State of New York, have originated and designed a Card-Board Card-Basket or Ornament; and I do hereby declare that the following is a full, clear, and exact description of the same, reference being had to the accompanying drawing, making part of this specification.

- 10 My ornamental card-basket has the general form and design of a barge with sail, the sides A being vertical, and parallel strips of card-board terminating at their rear ends in diagonal pieces B, and at their front ends in irregularly curved pieces C, the lower edges of these sides being inwardly inclined, as at D, to form somewhat the shape of the hull of a vessel. These inclined sides D are joined at their under edges by a flat sheet of card-board, 15 E, representing the floor of the vessel, the irregularly curved front ends C of the vertical strips A being united at their upper ends to represent the beak of the vessel, and the front ends of the inclined strips D and of the flat strip E being bent upward and united to each other and to the front of the strips A, forming the representation of the bow of the vessel. The diagonal pieces B are united in front by a plate of card-board, F, and in the rear 20 by a similar plate, G, which last-mentioned plate also incloses the end H of the hull, and a plate, I, extends across the top and from one diagonal piece B to the other, the diagonal pieces B, plates F, G, and I forming an

inclosed representation of a cabin, to the rear 35 of which is secured a piece of card-board, J, designed to represent a rudder, and a piece, L, to represent a standard with a staff, M. A mast, O, and spar P, at right angles to the mast, support a card-board representation of 40 a triangular sail, R.

The design thus produced may be made of perforated card-board, and ornamented by stitching of different-colored worsteds and by tassels s and pictures, and provided with cords 45 to represent braces and halyards for the mast and sail.

The entire design of the basket or ornament is intended to be stamped from sheets of card-board, so that the several parts will readily 50 fold and come together.

The interior of the design may be employed for holding cards or other articles, or the design may hang from a support as an ornament.

What I claim as my invention is—

A design for a card-board ornament or basket with vertical sides A, diagonal pieces B, curved pieces C, inclined sides D, bottom piece, E, plates F, G, and I, rudder J, standard L, and staff M, mast O, spar P, and sail R, all combined and united to form the general outline of a barge with sail, substantially as above described.

55 LIZZIE O. KOONES.
